UNITED STATES PATENT OFFICE.

MICHAEL DOYLE, OF ROCHESTER, AND FRANK GEBBIE, OF ST. JOHNSVILLE, NEW YORK.

CAN-CAPPING MACHINE.

SPECIFICATION forming part of Letters Patent No. 701,021, dated May 27, 1902.

Application filed June 21, 1901. Serial No. 65,390. (No model.)

To all whom it may concern:

Be it known that we, MICHAEL DOYLE, a resident of Rochester, in the county of Monroe, and FRANK GEBBIE, a resident of St. Johnsville, in the county of Montgomery, in the State of New York, citizens of the United States, have invented new and useful Improvements in Can-Capping Machines, of which the following is a specification.

This invention relates to a machine which is designed for closing the filling-openings in the tops of sheet-metal cans—for instance, cans used for putting up condensed milk, fruits, vegetables, &c.—by flanged sheet-metal caps, which are secured in the opening by bending the flange of the cap over the flange which surrounds the filling-opening and interlocking the flanges in such manner as to secure the cap tightly in the opening by a liquid-tight joint without solder.

One object of our invention is to employ a cap of shallow cup shape having a horizontal flange projecting outwardly from the upper end of the upright wall of the cap, so that the latter can be struck up in one operation ready for application to the can.

Another object of our invention is to produce a machine which will secure the cap in the filling-opening quickly and tightly by two successive crimping operations, consisting of a preliminary or partial crimping or bending of the horizontal cap-flange over the upright flange surrounding the opening and a final crimping operation, which presses the flanges tightly against each other and also interlocks the same.

Another object of our invention is to construct the machine in such manner that these crimping operations are performed automatically after the can and cap have been placed in the machine and the crimping instrumentalities have been started by the operator and so that these instrumentalities are stopped automatically when the cap has been secured in the opening, so that the capped can may be removed by the operator and another can put in the machine, when the cycle or series of operations is repeated.

In the accompanying drawings, consisting of three sheets, Figure 1 is a side elevation of

a can-capping machine embodying our invention. Fig. 2 is a front elevation of the upper part of the machine. Fig. 3 is a vertical longitudinal sectional view of the upper part of the machine. Fig. 4 is a vertical transverse sectional view, on an enlarged scale, showing the position of the preliminary and final crimping-rollers in the position they occupy just prior to commencing the crimping operations. Fig. 5 is a similar view showing the preliminary crimping-roller in operative position. Fig. 6 is a similar view showing the final crimping-roller in operative position. Fig. 7 is a similar view showing a different form of closure with the proper final crimping-roller and mandrel therefor. Fig. 8 is an enlarged horizontal sectional view on line 8-8, Fig. 1. Fig. 9 is a sectional view of the locking-bar and shipper-cam. Fig. 10 is a rear view of the shipper-cam. Fig. 11 is a side elevation of the same parts. Fig. 12 is a fragmentary vertical section of the can-support and its driving-spindle on an enlarged scale. Fig. 13 is a horizontal section on line 13-13, Fig. 12, looking upward. Figs. 14, 15, and 16 are diagrammatic views showing the different steps which are performed in securing the cap by an oblique crimped joint by means of the mandrel and crimping-rollers shown in Figs. 1 to 6. Figs. 17, 18, and 19 are similar views showing the different steps which are performed in securing the cap by an internally-beaded joint by means of the mandrel and crimping-rollers shown in Fig. 7. Fig. 20 is a side elevation of the actuating mechanism of one of the crimping-rollers on the scale on which these parts are shown in Figs. 4 to 8. Fig. 21 is an enlarged sectional view of the frictional driving mechanism on the cam-shaft.

Like letters of reference refer to like parts in the several figures.

The closure or joint by which the cap is secured in the flanged opening may be made in several ways. In Figs. 1 to 6 and 14 to 16 it is made by bending the closed flanges obliquely, and in Figs. 7 and 17 to 19 it is made by throwing an annular lip or bead out of the bottom of the cap below the upright flange surrounding the opening.

A represents the can to be capped; a, the

top of the can; a' , the filler-opening in the top, and a^2 the upright flange surrounding the opening.

B represents the cap, having the form of a shallow cup of the proper size to fill the opening when the cap is placed in the same with its horizontal flange b resting upon the upright flange a^2 of the can, as shown in Figs. 4, 14, and 17. The preliminary crimping operation illustrated in Figs. 15 and 18 consists in bending the horizontal flange of the cap down over the flange of the can to an oblique position. This operation is practically the same in the two styles of closure illustrated in the drawings, while the final crimping operations are different. In the closure illustrated in Figs. 1 to 6 and 14 to 16 the final operation consists in closing the flange and the upright wall of the cap tightly against the flange of the can and bending the closed flanges obliquely, as shown in Fig. 16, to interlock the flanges. In the closure illustrated in Figs. 7 and 17 to 19 the flanges remain vertical, and the final crimping operation consists of closing the flange and upright wall of the cap against the flange of the can and throwing a bead or annular lip b' out on the cap at the bottom thereof. Either closure can be produced by our improved machine by using instrumentalities of the proper shape.

The frame of our improved capping-machine consists of a lower part C and an upper part C', secured together in any convenient manner. Journaled in upper and lower bearings $c c'$ on the upper frame part C' is a vertical main driving-shaft c^2 , provided with a driving belt-pulley c^3 . This driving-shaft is provided near its lower end with a thrust-collar c^4 , which supports the shaft upon the lower bearing c' .

D indicates a can-supporting disk or plate which is mounted so as to be capable of rotation and of movement up and down in the following manner: The support D, which is provided with a marginal retaining-flange d for the can, is carried by the upper end of a shaft or spindle E, mounted to slide vertically in a sleeve E', Fig. 3, to which it is connected by means of a feather or key e , so as to rotate therewith. The sleeve E' is rotatably mounted in upper and lower bearings F F' on the upper frame part C'. Fixed to the sleeve below the upper bearing F is a belt-pulley G, driven from a pulley G' on the main driving-shaft c^2 by means of a belt G². It will thus be seen that the sleeve E' and the shaft E carried thereby are rotated and that the shaft is also vertically slideable in the sleeve. The sleeve is held against vertical displacement by any suitable means—for instance, by a flange e' at its upper end bearing against the upper side of the upper bearing F, and the hub of the pulley G bearing against the lower side thereof.

The shaft E is moved up toward the crimping devices to carry the can-support D into operative position by means of a lever H, ful-

crumed at h to a convenient part of the machine-frame. The lever carries at its front end a pivoted block H', which engages underneath the shaft E. While other devices will readily suggest themselves for this purpose, the construction just described is a desirable one. At its rear end the lever is pivotally connected to the lower end of a bar I, which we term the "locking-bar." This bar is loosely connected at its lower end by a link I' to an operating-lever I², (shown as a foot-treadle,) fulcrumed at its rear end to some suitable fixed part I³, attached to the floor or some other support. I⁴ indicates a spring secured to the treadle I² and to a suitable part of the frame for returning the treadle to its normal raised position after it has been released.

As it is desirable to automatically retain the shaft E and can-support D in the raised or operative position until the crimping is completed, and thereby relieve the operator from the necessity and exertion of holding the treadle down, the locking-bar I, above referred to, is employed. This bar passes loosely (see Fig. 3) through openings in the bearings F F' and has at or near its upper end a shoulder I⁵, adapted to engage a stop formed by a fixed part of the frame, into engagement with which it is thrown by the rearward pull of the link I' on its lower end when the treadle is depressed. As shown in Fig. 3, the shoulder at the upper end of the locking-bar is arranged on the front side of the bar and engages against the under side of a forwardly-projecting part I⁶ of the frame, which is provided with an opening I⁷, in which the upper end of the bar plays. When the treadle is depressed, the upper end of the bar is lowered, with its shoulder below the part I⁶ of the frame, and also thrown forward, so that the shoulder engages against the under side of the frame part I⁶, which forms a stop for the locking-bar. In this position of the bar the latter holds the treadle depressed and the can-support elevated in its operative position. By pressing the upper end of the locking-bar backward it is released from this stop, and the spring of the treadle then raises the latter and the locking-bar and lowers the can-support. The locking-bar remains in this locked position to hold the can-support up until the capping operation has been completed, when the bar is automatically released by means which will be hereinafter described.

J represents an upright spindle or shaft which is arranged centrally above the can-support and which carries at its lower end a mandrel J', Figs. 1 to 6 and 14 to 16, or J², Figs. 7 and 17 to 19, which enters the cavity of the cap. This mandrel is secured to the spindle preferably by detachable connections—for instance, a screw-thread. The mandrel-shaft J is rotatably mounted in an upper bearing K and a lower bearing K', the latter being formed in the part I⁶ of the frame. K² is a pulley which is secured to this shaft between these

bearings and which is driven by a belt K^3 from a pulley K^4 on the driving-shaft c^2 . The mandrel-shaft J is adjustable vertically, and for this purpose it is journaled and supported with its upper portion in a vertically-adjustable bushing k in the upper bearing K . The shaft is provided below the bushing with a collar l and above the bushing with a washer k' and nut k^2 . The bushing is externally screw-threaded and secured in a screw-threaded opening in the bearing K , in which it is clamped by a jam-nut k^3 .

The crimping devices comprise a preliminary crimping-roller L and a final crimping-roller M . These rollers are movably supported to be brought into contact with the work successively, one moving to the work, crimping, and then returning, after which the other performs similar functions. A desirable mechanism for accomplishing this is constructed as follows: The preliminary crimping-roller L is loosely mounted on a depending stud-shaft L' , carried by an arm L^2 of the front end of a horizontal rock-shaft L^3 , which latter is journaled in suitable bearings L^4 in the upper frame part at one side of the mandrel-shaft. This shaft L^3 has secured to its rear portion an actuating rock-arm L^5 , provided at its end with an antifriction-roller L^6 . The other or final crimping-roller M is similarly mounted at the opposite side of the mandrel-shaft on a depending stud-shaft M' , carried by an arm M^2 on a rock-shaft M^3 , journaled in bearings M^4 and having secured thereto an actuating rock-arm M^5 , provided at its ends with an antifriction-roller M^6 . These arms project upwardly toward a horizontal cam-shaft N , which is journaled in a rear bearing N' , formed in the upper frame portion C' , and a front bearing N^2 , formed in the frame portion I' . Secured to the shaft N conveniently between its bearings N' and N^2 are two actuating-cams L^7 and M^7 , arranged one behind the other. The cam L^7 is so located and fashioned as to engage in the rotation of the shaft with the antifriction-roller L^6 and swing the arm L^5 outwardly, which causes the preliminary crimping-roller L to move in toward the mandrel and to its work. The cam M^7 is so located and fashioned as to engage in the rotation of the shaft with the antifriction-roller M^6 just about the time that the other can passes from engagement with its arm and causes the final crimping-roller M to move into operative position. Each of the cams L^7 and M^7 gradually increases in radius or depth toward its rear end, thus gradually moving the crimping-rollers with increasing pressure toward the work. Any desired means may be employed for returning the crimping-rollers to their inactive position—for instance, springs L^8 M^8 , which hold the actuating-arms against the cams. A convenient way of applying these springs consists in connecting the same not directly to the actuating-arms, but to arms L^9 M^9 , loosely mounted on the shafts L^3 M^3 , re-

spectively. As shown in Figs. 8 and 20, the arm M^9 of the final roller carries an adjusting-screw M^{10} , which is held against a lug M^{11} on the arm M^9 by the tension of the spring and whereby the spring tension can be adjusted. The spring L^8 of the preliminary crimping-roller is connected with the arm L^9 in a similar manner.

The stop device illustrated in the drawings for bringing the crimping instrumentalities to rest and lowering the can-support after the closure is completed is as follows:

Secured to and rotating with the shaft N is a shipper-cam O , which has an oblique shipper-face O' , adapted to engage with the front side of the locking-bar I , Fig. 9, and move the same rearwardly to disengage its shoulder I^5 from the stop, thus permitting the locking-bar and treadle to be moved upward to their normal position by the spring I^4 , which, through the lever H and its connections, lowers the can-support. The shipper-cam carries at the rear end of its oblique shipper-face O' a stop lug or projection O^2 , which after the locking-bar has been released and thrown upward engages against the side of the bar. The latter now stops the further rotation of the cam-shaft N , and this occurs after the crimping-rollers have completed one cycle of operations and the can-support has been lowered with the capped can and leaves the parts in position for receiving a fresh can to be capped and repeating the cycle of operations.

To permit the stopping of the cam-shaft in this manner, the shaft is driven by a driving mechanism including a friction-clutch device of any suitable construction. That which is shown in the drawings, Figs. 1, 2, and 21, for this purpose is constructed as follows: On the rear portion of the cam-shaft is loosely mounted a bevel gear-wheel P , which is driven by a pinion P' , fixed on the upper end of a vertical counter-shaft P^2 , which is journaled in bearings in the upper frame part C' . This counter-shaft is provided with a pulley P^3 , which is driven from a pulley P^4 on the drive-shaft c^2 by a belt P^5 . The gear P is not fixed to the shaft N and only drives the latter through the medium of a friction-clutch device, so that the shaft N can be stopped, while the gear P continues its rotation. The friction-clutch illustrated in the drawings comprises friction-rings Q , of leather or other suitable material, on each side of the hub of the gear-wheel P , a fixed collar Q' on the shaft, a clamping-ring Q^2 , and a clamping-nut Q^3 screwed onto the screw-threaded end of the shaft N . The clamping-ring Q^2 is preferably keyed to the shaft to prevent its turning thereon, and thus causing the turning of the clamping-nut.

Inasmuch as the mandrel shaft or spindle J is journaled in fixed bearings and the mandrel is necessarily smaller than the cavity of the cap, to enable the mandrel to be inserted for performing its function and to be with-

drawn it is necessary that the can should be able to move laterally with each crimping-roller to the mandrel. To accomplish this without requiring the can to shift or rock on its support, the latter is loosely mounted on the upper end of its carrying-spindle E in such manner that the support is capable of a slight wabbling or tilting movement. For this purpose the hub *r* of the can-support is provided with a screw-threaded socket *r'*, into which is screwed the end of the shaft E, which, as will be seen from Figs. 12 and 13, is so small as to make a loose connection. A locking bolt or key S is arranged on the under side of the can-support and projects inwardly through an opening *s* in the hub *r* and engages in one of a series of upright grooves *t* in the end of the shaft. The bolt or key has on one side a laterally-projecting ear *s*², provided with a longitudinal slot *s*³, through which passes a screw *s*⁴ into the support. A spring-plate *u* is interposed between the head of the screw and the ear *s*² of the bolt or key. Upon withdrawing this locking-bolt from the groove in the shaft the can-support can be readily adjusted up or down on its shaft. The support is secured in its adjusted position by engaging the connecting-key in the next adjacent groove of the spindle. The key compels the support to turn with the shaft and allows the support the desired limited wabbling or tilting motion.

The can-support and the mandrel are rotated rapidly, while the crimping-rollers are not driven, but are simply pressed against the work. For forming the oblique closure illustrated in Figs. 14 to 16 the mandrel J', having an oblique face *j*, and the final crimping-roller M, Figs. 1 to 6, are used. For forming the internally-beaded closure, as shown in Fig. 7 and Figs. 17 to 19, the mandrel J², having a bead *j'* at its end, Fig. 7, and the final crimping-roller *m*² are used. The can, with the cap placed in the flanged opening in its top, is placed upon the support. The operator then depresses the treadle, whereby the can-support is raised to its operative position, in which the mandrel projects into the cavity of the cap. The raising of the support lowers the locking-bar and withdraws the latter from the locking-lug of the shipper-cam. This releases the cam-shaft and at the same time locks the bar against the stop to hold the can-support in its operative position. The cam-shaft is now rotated by the frictional driving gear. The preliminary crimping-roller is next swung against the work and partially bends the cap-flange. The final crimping-roller is next swung against the work, whereby the closure is completed. The shipper-cam then releases the locking-bar from the stop, whereby the can-support is lowered and the capped can is withdrawn from the mandrel. When the cam-shaft has completed a revolution, the stop-lug on the shipper-cam is arrested by the locking-bar and stops the further rotation of the shaft. The capped

can is now removed by the operator and a fresh can placed on the support, when the operation is repeated.

In moving against the work the rollers swing downwardly and inwardly into the cavity or depression of the upper head of the can, in which the collar or flange surrounding the filler-opening and the cap are arranged, and in moving away from the work the rollers move upwardly and outwardly out of the cavity or depression.

We claim as our invention—

1. In a can-capping machine, the combination of a rotary support for the can to be capped, a rotary crimping-mandrel arranged above said support and adapted to enter the depression of the cap, an upright rock-arm mounted on a horizontal pivot, a stationary support for said pivot, a crimping-roller mounted directly on said rock-arm below the pivot-line thereof to swing with the rock-arm downwardly and inwardly and upwardly and outwardly, and a rotary cam whereby said rock-arm is actuated to swing the crimping-roller downwardly and inward against the cap, substantially as set forth.

2. In a can-capping machine, the combination of a rotary support for the can to be capped, a rotary crimping-mandrel arranged above said support and adapted to enter the depression of the cap, upright rock-arms mounted on independent horizontal pivots, a stationary support for said pivots, preliminary and final crimping-rollers mounted, respectively, directly on said rock-arms below the pivot-lines thereof to swing with the rock-arms downwardly and inwardly and upwardly and outwardly, actuating-arms on said rock-arms, a horizontal rotary shaft arranged between said actuating-arms, and cams on said shaft engaging said actuating-arms and actuating said rollers successively, substantially as set forth.

3. The combination of a crimping-mandrel, a can-support, a crimping device movable toward and from said mandrel, an actuating device for said crimping device, a frictional driving mechanism for said actuating device, and a releasable stop device whereby said actuating device is held against further action when the crimping operation has been performed, and which is released for again starting said actuating device, substantially as set forth.

4. The combination of a crimping-mandrel, a can-support, a crimping device movable toward and from said mandrel, a rotary cam for actuating said crimping device, a frictional driving mechanism for actuating said cam, a rotary stop controlling the movement of said cam, and a releasable stop against which said rotary stop engages when the crimping operation has been performed, substantially as set forth.

5. The combination of a crimping-mandrel, a can-support, which is movable toward and from the same, a crimping device which is

movable toward and from the mandrel, an actuating device for said crimping device, a frictional driving mechanism for said actuating device, a releasable stop device connected with the movable can-support for holding the same in its operative position, and a stop device by which the further action of said actuating device is prevented when the crimping operation has been performed, substantially as set forth.

6. The combination of a crimping-mandrel, a can-support, which is movable toward and from the same, a crimping device which is movable toward and from said mandrel, a cam for actuating said crimping device, a frictional driving mechanism for said cam, a locking-bar connected with the can-support, a shipper-cam for releasing the locking-bar, and a stop on said cam for engaging against said bar and holding the actuating-cam against further rotation, substantially as set forth.

7. The combination of a crimping-mandrel, a can-support which is movable toward and from the same, preliminary and final crimping devices which are movable toward and from said mandrel, a rotary cam-shaft, cams secured to said shaft for actuating said crimping devices, a frictional driving mechanism for said shaft, a locking-bar connected with said can-support, and a shipper-cam also secured to said shaft and provided with a shipper-face for releasing said locking-bar and with a stop-lug for engagement against said bar and preventing the further rotation of said cam-shaft, substantially as set forth.

8. The combination of a stationary frame, a crimping-mandrel, a can-support which is movable in said frame toward and from the mandrel, a locking-bar connected with the can-support, a stationary stop on said frame against which the locking-bar engages when the support is in its operative position, a crimping device which is movable toward and from said mandrel, and a shipper-cam by which the locking-bar is released from said stop when the crimping operation has been performed, substantially as set forth.

9. The combination of a stationary frame, a crimping-mandrel, a can-support which is movable in said frame toward and from the mandrel, a locking-bar connected with the can-support, a stationary stop on said frame against which the locking-bar engages when the support is in its operative position, a crimping-roller which is moved toward and from said mandrel, an actuating-cam for said

roller, and a shipper-cam movable with said actuating-cam for releasing said locking-bar from said stop, substantially as set forth. 60

10. The combination of a crimping-mandrel, a crimping device movable toward and from said mandrel, a can-support arranged below said mandrel and movable toward and from the same, an upright locking-bar movably connected near its lower end with said can-support, a treadle connected with the lower end of said locking-bar, a stop with which the upper end of said bar engages, and means for automatically releasing said bar from said stop, substantially as set forth. 70

11. The combination of a crimping-mandrel, a crimping device movable toward and from the same, a horizontal shaft provided with an actuating-cam for said crimping device, a can-support arranged below said mandrel and movable toward and from the same, an upright driving-shaft, driving connections extending from said shaft to said mandrel and said can-support, a frictional driving mechanism interposed between said driving-shaft and said cam-shaft, a locking device for supporting said can-support in its operative position, and a shipper-cam for releasing said locking device, substantially as set 85 forth.

12. The combination of a crimping-mandrel, a crimping device movable laterally toward and from the mandrel, a can-support facing the mandrel, a rotary supporting-spindle for the can-support, a loose connection by which the can-support is attached to its spindle and which permits of a limited lateral movement of the can-support on the spindle, and a coupling device by which the can-support is rotated with the spindle, substantially 90 as set forth. 95

13. The combination of a can-support having an internal screw-thread, a supporting-spindle which is provided with an external 100 thread which fits loosely in the thread of the support and which is constructed with an upright groove, and a connecting-key which is attached to the support and movable into and out of said groove, substantially as set 105 forth.

Witness our hands this 10th day of June, 1901.
